UNITED STATES PATENT OFFICE

ROBERT GALLOWAY ROSS, OF CHARLOTTE, NORTH CAROLINA, ASSIGNOR TO MAE ELLIS, OF CHARLOTTE, NORTH CAROLINA

WARDROBE

Application filed November 22, 1929, Serial No. 409,081. Renewed December 15, 1932.

The object of my invention is to provide a novel wardrobe especially intended for school use, to provide novel means for operating the doors of the wardrobe, and to provide the 5 novel construction and arrangement of parts hereinafter described in detail; and to provide a novel double door lock, etc.

I attain these and other objects of my invention, by the device illustrated in the accompanying drawings, in which,—

Figure 1 is a front elevation of my invention;

Fig. 2 is a section through the wardrobe showing a detailed plan view of the operating 15 mechanism;

Fig. 3 is a detailed view of the chain adjusting mechanism;

Fig. 4 is a detailed plan view of a safety device which I have invented for use in this 20 wardrobe;

Fig. 5 is a detailed view, partly in section and partly in elevation of one of the door stiles;

Fig. 6 is a detailed view through one of the 25 doors, showing the veneer or reinforcing strips used;

Fig. 7 is a detailed sectional view of a door having a modified type of veneering or paneling;

Fig. 8 is a detailed view, partly in section and partly in elevation of a locking device;

Fig. 9 is a vertical sectional view on line 9—9 of Fig. 1;

Fig. 10 is a vertical sectional view on line 35 10—10 of Fig. 1;

Fig. 11 is a horizontal sectional view on line 11—11 of Fig. 1; and

Fig. 12 is a horizontal detailed sectional view on line 12—12 of Fig. 1.

40 Like characters of reference designate like parts in each of the several views.

Referring to the accompanying drawings, I provide a suitable wardrobe frame having the sides 5 and top 6 with the front frame or 45 casing 7 and an upright casing strip 8 between the two doors 9 and 13. The doors 9 and 13 each have bottom rails 11, top rails 12 and stiles 14, the doors being provided with any suitable artistic trimming strips, not 50 numeralized.

Referring to Figs. 1 and 2, I provide a key shaft 15 which is directly connected to, or carries, the bottom gear 18, which gear in turn is arranged to mesh with gears 19 and 20, which gears are mounted on the shafts 25 and 26 respectively. The shaft 25 carries the drum 44 and shaft 26 carries the drum 45, as shown. Cables 21 are connected with the drums 44, 45 at one end, (the drums being arranged as shown in Fig. 2) and adjustably 60 connected with the hangers at the other end (as shown in Fig. 3). The cable 22 needs no adjustment because the weight 23 pulls all the slack out of the cable, but cable 21 may be adjusted by means of the bolt 32 and nut 65 33 as illustrated in Fig. 3.

The shaft 25 has its end positioned in alignment with aperture 27 in the casing 43, while the key shaft 15 has its key end positioned in alignment with the aperture 28 and the rod 70 26 has its end positioned in alignment with the aperture 29, as shown in Fig. 2. Casing 43 is suitably attached to perpendicular studing or frame work 14 as shown in Fig. 2.

The chains or cables 21 for each of the two 75 doors are carried over rollers 24 and have their other ends attached by a bolt 32 and nut 33, as shown in Fig. 3 to the portion 31 of a hanger 30 which is affixed to the bottom portion of the wardrobe door. Cables 22 are 80 each attached at one end to a weight which counter-balances the weight of the wardrobe door to make it easier to open by sliding upward vertically as indicated in dotted lines in Fig. 1. The rollers 24 are mounted on a 85 suitable portion of the casing or framework, as shown in Figs. 1, 9 and 10. Spring 51 is attached at one end to the door, as shown in Fig. 4.

As shown in Fig. 3, I provide a convenient 90 means for adjusting the length of the chain or cable 21, consisting of a screw-threaded pin 32 which passes through an apertured portion of the plate 31 and is adjustably held to the plate by a suitable nut 33. 95

I provide novel means for locking both doors in closed position to prevent theft of articles from the wardrobe, or to prevent opening of the wardrobe by children during school sessions or to provide for the conven- 100

ient locking and unlocking of the wardrobe doors by the children without the necessity of providing them with keys.

As illustrated in Fig. 8, I provide a drawer 34 in the upright 8 of the wardrobe casing. Above this drawer is a hook or nail 36 to which the short chain 37 may be detachably engaged. This chain 37 is secured to the pivotally connected links 38 by the double link 41. Links 38 are pivotally connected to the link 41 and at their other ends are pivotally connected to the bars 39. The bars 39 are slidably mounted in the brackets 40 mounted on suitable studding, and slidable into the slots 42 in the stiles 14 of the wardrobe doors 9 and 13, as shown in Fig. 1.

I provide suitable means for holding the links 38 in their elevated and unlocked position with the bars 39 withdrawn from engagement with rails 14 of the wardrobe doors 9 and 13, as shown in Fig. 8. Such means consist preferably of a spring 57 or other suitable means for holding the links 38 in a normally elevated position. Spring 57 has its upper end suitably attached to a hook or the like.

Referring to Fig. 4, there is illustrated a safety device which I prefer to employ in connection with the wardrobe doors, consisting of the rods 49 pivotally connected to the link 47 which in turn is attached to the pin 48 carried by the chain 22, which passes over the roller 24 as shown in Fig. 1, and is attached to the counterweights 23, which balances the weight of the wardrobe doors. The rods 49 run through lugs 53 attached to the bottom rail of doors, and are held in place against the board frame by said lugs or staples which function as bearing elements, the rods working freely back and forth through the lugs 53. Two pins 53a pass through said rods near the end at a point on each side of the two lower lugs 53 to keep the rods from being pulled out of the lugs by the weight of the door. The counterbalancing weights attached to chain 22 are always pulling on these rods 49 to keep them from engaging with slots 54. When the chain breaks or the weight is released spring 51 immediately pulls rods 49 into locking position. The rods 49 have their ends flattened to better engage the slots 54 of the wardrobe frame, so that should the cable or chain 22 break off, or the weight become detached from it, the doors could not drop suddenly to cause possible injury, but the free ends of the rods 49 would engage in the slots 54 as shown in Fig. 4 and stop further dropping of the door.

I prefer to provide a suitable expanded spring 51 attached to the end 50 of the pin 48 to pull down the safety mechanism when chain breaks causing it to engage slots 54.

Referring to Fig. 5, there is illustrated the detail of the door stiles, the member 55 be-

ing an upright of the door casing. I prefer to provide floating rollers 16 which are mounted on the bearing 56. This bearing 56 is a floating bearing which has a resilient movement relative to the door stile 14 by means of the springs 57. Any swelling of the door is taken care of by the springs 57 which allow for a suitable automatic adjustment of the bearing 56 and rollers 16 which it carries. The rollers 16 make easy operation of the doors possible without the possibility of their sticking from any cause.

Referring to Figs. 6 and 7, there is illustrated two different types of door panels which I may employ. In the form of the mechanism illustrated in Fig. 6, I provide a center wood panel strip 60 on either side of which I provide the outer strips or sheets of a suitable composition panel 59, or other suitable material. The stiles 14 are entirely of hardwood and are fastened to the outer hardwood strips 14' which extend entirely around the door and slide within the wardrobe casing members 5. The wood strip 14' is suitably affixed to the stile 14 of the wardrobe door by suitable means, such as the screws 58.

This hardwood strip 14', can be attached to stiles and rails after any warping has taken place, and when on the stiles will be straight and true and permit of perfect operation of the door and in connection with the floating roller 16 will permit of easy operation of the door, regardless of warping. This strip on the bottom of the door will close the crack or opening when the door is raised to its full height, making a neat finished appearance to the wardrobe. This strip may be eliminated on top of the doors. Leather or other flexible material may be substituted.

In the form of my invention illustrated in Fig. 7, I provide an inner strip 63 of felt adjacent the three-ply wood panel 61 over which is positioned the fiber board panel 62, while on the other side of the door, I may provide a sheet of natural slate or rigid composition blackboard. The soft felt material 63 prevents strain or breakage of the blackboard or slate sheet 64 in case of warping or shock. At the bottom, the blackboard or slate panel 64 would rest on a strip of rubber mounted on a rail of the door, not shown.

The operation of the invention has been indicated in connection with the description of the construction and parts as hereinbefore set out. The doors of the wardrobe are vertically slidable as indicated by dotted lines in Fig. 1. The weight of the doors is counterbalanced by the weight 23 which is attached to a suitable chain or cable 22 which in turn is connected to a suitable hanger, preferably a safety hanger attached to the door, as illustrated in Fig. 4, whereby if the cable or weight should break, the rods of the hanger by reason of spring 51, will engage in the

slots 54 and prevent the door from dropping suddenly to cause injury.

The doors are raised by the operation of a conventional crank (not shown), which is 5 detachably connected with the key shaft 15 to operate the under gear 18, which in turn actuates the gears 19 and 20 operating the drums 44 and 45, respectively, which are mounted on the same shafts with these gears.

10 Attached to the drums are suitable linear elements, namely the cables or chains 21 which run over the rollers 24, the ends of said cables or chains being attached to a suitable hanger which in turn is affixed to 15 the bottom of the wardrobe doors.

The operation of the crank (not shown) which is detachably engaged to the shaft 15 operates the gear 18 and meshing gears 19 and 20 to turn the drums 44 and 45 and thus 20 operate the linear elements, namely the chains or cables 21 to simultaneously (or selectively) raise and lower the doors 9 and 13. The selection of which door is to be operated is accomplished by shifting one of 25 the gears 19 or 20 out of engagement with the gear 18 said gears being normally held in proper engagement therewith by the spring 46. This shifting of the gears for selection of operation of the doors is done 30 by pushing inward the shaft on which the particular gear is mounted which it is desired to throw out of mesh with the gear 18. The other gear and drum mounted on the same shaft would then be operated alone to 35 raise the wardrobe door on that side of the wardrobe.

The shafts 25 and 26 are slidably mounted as illustrated in Fig. 2, said shafts carrying drums 44 and 45 and gears 19 and 20, respectively. Said shafts also are operatively connected with the springs 46, which springs normally hold them in engagement with the gear 18, which gear is on the shaft operated by the crank used to raise and lower the doors 45 as illustrated in Fig. 2.

To facilitate operation of the doors and to allow for warping or for variation in size of the doors due to temperature changes the floating rollers 16 are provided, mounted on 50 the lower and upper portions of the edges of the doors and rollably engaging the uprights 55 of the wardrobe frame. The springs 57 permit of a resilient movement of the rollers, thus making the door automatically adjustable. This construction not only takes care of temperature changes but warping of the door due to dampness or otherwise.

I prefer to provide a novel locking mechanism for simultaneously locking both doors 60 as illustrated in detail in Fig. 8 and diagrammatically in Fig. 1, consisting of the slideable locking bars 39 which are normally held out of locking engagement with the correspondingly shaped apertures in the rails of the respective wardrobe doors but which may be

operated into engagement with said doors to lock them in a closed position. These slideable locking bars are operatively connected by pivotally connected links to which a chain is connected and which chain may be detachably secured to a hook or the like fastened to the inside casing just above the drawer 34 to hold the locking bars in locked position or to permit of their being withdrawn from locked position and held in a normally retracted position by a suitable spring 57, or other suitable equivalent means for holding the bars in retracted position. The drawer may or may not have a conventional lock on it as desired. This construction makes it possible for the children to lock and unlock their wardrobe doors without the necessity of providing an individual key. The construction also provides a means, if desired, for the locking of the wardrobe by an official of the school by concealed mechanism to prevent unauthorized removal of articles of clothing from the wardrobe during school sessions.

The guard strips 14' affixed to the rails and stiles of the door function to improve 90 the operation of the door and to give it a more finished appearance when in open or closed position. I also may provide panels comprising layers of different materials as heretofore described to permit the use of the doors for bulletin boards if desired and to provide means for preventing breakage of frangible material used in constructing these bulletin boards.

What I claim is:

1. In a wardrobe, the combination of a wardrobe frame, a plurality of vertically slideable doors mounted in said frame, a hanger affixed to the bottom of each of the doors, weights for counter-balancing the doors, linear elements connecting the aforesaid weights with the aforesaid hangers on the doors, linear elements connected with the hangers, drums with which the last mentioned linear elements are connected and manually operable means connecting with the aforesaid drums for simultaneously raising and lowering both of the doors.

2. In a wardrobe, the combination of a wardrobe frame, a plurality of vertically slideable doors mounted in said frame, a hanger affixed to the bottom of each of the doors, weights for counter-balancing the doors, linear elements connecting the aforesaid weights with the hangers on the aforesaid doors, a second set of linear elements connected with the hangers affixed to the bottom of the doors, drums with which the other ends of said linear elements are connected, manually operated means connected with said drums for simultaneously raising and lowering both of the doors, and means for permitting of selective operation of either of the doors independently of the other.

3. In a wardrobe, the combination of a

wardrobe frame, doors slidably mounted in said wardrobe frame, manual operable means for simultaneously or independently raising and lowering the doors, counter-weights operatively connected with the doors to counter-balance same, linear elements connecting the aforesaid weights with the doors, a safety device operatively connected with the aforesaid means for raising and lowering the doors and to which a counter-weight is attached, said safety device comprising pivoted, diagonally depending arms, the frame of the door having oppositely spaced notches with which the arms of the safety device are adapted to operatively engage in the event of breaking of the linear element or of the weight becoming disconnected from same.

ROBERT GALLOWAY ROSS.
